UNITED STATES PATENT OFFICE.

HALSEY W. TAYLOR, OF WARREN, OHIO.

DRINKING FOUNTAIN.

Application filed August 14, 1922. Serial No. 581,650.

This invention relates to an improvement in drinking fountains, and the main object of the invention is to provide a simple and effective means for automatically regulating a fluctuating supply of water so as to produce a steady and uniform discharge of the water and a stable drinking column of fixed shape. This automatic regulator is further incorporated as a part of a combined supply and drain fitting for a drinking fountain bowl, all as hereinafter shown and described and more particularly pointed out in the claims.

In the annexed drawings, Fig. 1 is a top view of a drinking fountain bowl embodying my invention, and Fig. 2 is a vertical section centrally of said bowl and the supply and drain fitting therein. Fig. 3, is a horizontal section on line 3—3 of Fig. 2, and Fig. 4 is an enlarged sectional view on line 4—4 of Fig. 2. Fig. 5 is a perspective view of the floating plunger or balance weight, and Fig. 6 is a side view of the bent or relief member without said plunger or weight. Fig. 7 is a cross section of the supply fitting on line 7—7 of Fig. 3. Fig. 8 is a diagram showing the working action of the automatic regulator.

The invention comprises a drinking fountain bowl or basin 2 having a round boss 3 at its bottom side and a drain opening 4 extending through this boss. An annular seat 5 within the bowl and boss supports a perforated drain plate 6 having a hollow central protuberance 7 which may be of hexagonal shape externally to permit a wrench to be applied thereto from the inside of the bowl or basin.

Protuberance 7 has a shallow chamber 8 formed in its upper end by a cross wall 9 which has a screw-threaded intake opening at its center communicating with this chamber, and a series of vertical outlet ducts 10 pass downwardly from chamber 8 into a concaved discharge space 11 which is bordered by a downwardly-extending flange or skirting 12. The circle of drain openings 13 in plate 6 are located between this skirting and the rounded seating edge 14 of the plate, and all the water discharged into the bowl or basin passes freely through the drain plate into the hollow enlargement 15 of a combined supply and discharge fitting 16 which is clamped to the bottom side of boss 3. A sealing washer or rubber gasket 17 is interposed between boss 3 and the flat seat 18

at the upper end of fitting 16, and clamping of the parts of the bowl or basin is effected by rotating drain plate 6 and screwing it over the upper screw-threaded end of a vertical nipple or extension 19 centrally affixed within the fitting in open communication with a central supply space 20. Two parallel channels 21 and 22 respectively of different length extend through a lateral arm 65 or branch 23 of the fitting and open into space 20, the longer channel 21 having a water supply connection 24 at the bottom side of its extremity, and the shorter channel having a vertical outlet at the top side 70 of the fitting in the form of a coupling enlargement or bell 25 which is of sufficient length to permit its engagement with the bottom side of the bowl, using a rubber washer or gasket 26 to promote sealing at 75 the joint when clamping is effected through the medium of the stream delivering and forming member 27. Thus, member 27 has a reduced screw-threaded shank 28 adapted to screw-engage coupling bell 25 in clamping 80 the fitting upon the bowl, and the head of member 27 is hollow and provided with two angularly-related openings 28 and 29 which converge to effect a confluence of two small jets of water within the bowl above a perforated guard 30. A single curving stream of water or arched drinking column is thereby formed which descends into the opposite end of the bowl, providing the length of the arched stream remains substantially constant and fixed. This latter result is only possible where a constant and unvarying pressure is employed, but in general the pressure and flow of water on the supply side varies a great deal especially where 85 other taps permit the withdrawal of water at other places in the same supply line. Excess pressure can be guarded against by placing a regulating valve at some place in the supply line, and in the present fitting 90 I employ for that purpose a small regulating screw 31 which passes upwardly through arm 23 into channel 21 to restrict in greater or lesser degree the flow of water passing into the fitting and out of the nozzle or delivery member. But such a regulator in itself does not effectively guard against fluctuations in the supply and a changing drinking stream or column; therefore I have provided a floating weight or plunger 32 95 which is constantly exposed to the water on the pressure or supply side of the fitting 100 which is constantly exposed to the water on the pressure or supply side of the fitting 110

and which is adapted to open and close a vent or relief orifice 33 particularly arranged to overflow or discharge into the drain side of the fitting. Plunger 32 is solid and cylindrical and seated to move freely within the upper end of the tubular extension or nipple 19, its upward movement being limited however, by the closed top of chamber 8. This plunger has a semi-spherical or rounded projection 34 at its bottom side which is adapted to partially protrude into the round vent orifice or outlet 33 in the transverse division wall of nipple 19 and to seat upon the circular edge 15 of this vent orifice opposite a series of escape openings 36 in the side of the nipple. The bottom side of the plunger surrounding the base of rounded projection 34 is also expressly shaped to utilize the escaping 20 water in the most effective way to hold the plunger in a state of suspension and equipoise while the water is escaping. In other words, the bottom side of the plunger is slightly dished or channeled on a straight 25 flaring line 37 from the base of the projection to the outer bottom edge of the plunger so that the water in jetting from the vent orifice will strike the beveled surface 37 surrounding the projections and operate to lift and uphold the plunger before 30 being deflected outwardly and downwardly into and through the side openings 36. In operation this plunger serves as a gravity valve to keep the vent orifice closed or 35 nearly closed while the pressure or flow of water is normal, or say as fixed by the regulating screw 31, but when the supply fluctuates and the pressure or volume of water is in excess of the needs or tends to elongate 40 the arched drinking stream, relief is immediately afforded by uplift of the plunger until normality of the supply is again established. I also find that a flat-bottomed plunger will work fairly well but not as 45 sensitively or surely as the plunger described, the conditions of test being equal.

The upper end of nipple 19 is slotted to permit the escape of water passing upwardly around the plunger, especially in 50 the event that drain plate 6 is screwed down until the top of protuberance 7 engages the upper end of nipple 19. A second regulating screw 38 may also be employed to restrict the flow of water passing through 55 channel 22, and this screw is preferably located at the upper side of the fitting closely adjacent nipple 19 where it will be covered and concealed by drain plate 6 but nevertheless accessible for adjustment when 60 said plate is removed.

What I claim, is:

1. A method of producing uniformity of delivery in a drinking stream projected at an angle to the vertical under fluctuating conditions in the water supply, which con-

sists in regulating the amount of water flowing through a delivery nozzle to maintain a predetermined minimum pressure to produce an arched drinking stream of substantial height, and in venting a part of the supply under a constant counter-pressure extraneous of the water supply to compensate fluctuations above said predetermined minimum pressure in the water supply.

2. A drinking fountain, comprising a water supply fitting having a discharge nozzle adapted to deliver a constant stream of water at an inclination to the perpendicular, and a water venting device on the intake side of said nozzle, having a water balancing weight constantly exposed to the flowing water escaping at said venting device so as to produce a steady drinking column of fixed shape regardless of fluctuations in the supply.

3. A drinking fountain, comprising a water supply fitting adapted to discharge a constantly flowing stream of water in arched drinking-column formation, having a regulating valve in the water supply line adapted to restrict the flow of water passing through the fitting, in combination with water venting means open to the said supply line having a water balancing member constantly exposed to the water passing therethrough and arranged to maintain the arched drinking column in fixed shape during fluctuations in the supply.

4. In a drinking fountain, a fitting having a drain opening and a supply passage, a perforated plate covering said opening, and a water balancing member positioned under said plate in discharge communication with said drain opening.

5. In a drinking fountain, a supply fitting having a drain opening and a supply passage, a perforated drain plate for said opening, and a restricted venting device for said supply passage having a water balancing weight in the line of communication between said supply passage and drain opening.

6. In a drinking fountain, a supply fitting having a drain opening and a supply passage, a perforated plate opposite said opening, and a water balancing weight beneath said plate in constantly open communication with said supply passage and drain opening.

7. In a drinking fountain, the combination of bowl having a drain opening, with a nozzle discharge member and a fitting having a supply passage, a nipple in communication with said supply passage having a restricted opening discharging into said drain opening, and a loose plunger within said nipple in constant exposure to the water passing through said passage.

8. A supply and drain fitting for a drinking fountain, comprising a hollow body having a vertical drain outlet and a horizontal

supply passage provided with a relief nipple opening into said drain outlet, an automatic valve within said relief nipple, and a drain plate connected with said nipple adapted to 5 clamp said fitting to a basin.

9. A supply and drain fitting for a drinking fountain having a vertical drain passage, a flat seat surrounding the upper end of said drain passage, a supply passage extending 10 into said drain passage, a relief nipple open to said supply passage and extending upwardly through the center of said seat, a relief valve within said nipple, and a drain plate adjustably connected with said nipple 15 and covering said valve.

10. A supply and drain fitting for a drinking fountain, having a vertical drain portion and a lateral branch provided with intake and outlet supply passages, said drain 20 portion having an annular seating surface at its top and said branch having a coupling terminal for the supply outlet adjacent said seating surface.

11. A supply and drain fitting for a drinking fountain, comprising a hollow body having a lateral branch provided with parallel 25 supply passages communicating with each other centrally within said body and terminating at their outer ends in an inlet and outlet, respectively, a tubular member extending centrally upward from said body and open to said supply passages having a relief orifice and side escape openings, a plunger loosely seated within said tubular member opposite said orifice, a drain and clamping plate connected with the upper end of said tubular member and a delivery nozzle connected with the supply outlet.

12. In a drinking fountain, the combination of a bowl having a drain opening, with

a delivery drinking-stream fitting having a supply passage, a drain plate for said opening, a venting nipple open to said supply passage beneath said plate, means associated with said supply passage adapted to regulate 45 the amount of water passing therethrough, and a weight positioned opposite said venting nipple adapted to automatically regulate the velocity of water discharged from 50 said fitting.

13. In a drinking fountain, the combination of a bowl having a drain opening, with a delivery nozzle and fitting having a water supply passage, a drain plate for said opening, a venting nipple secured to said fitting 55 having a restricted outlet and a loose plunger opposite said outlet having a rounded central portion and a depending skirt adapted to deflect the water issuing from said outlet and to balance the outflow of the water 60 from the nozzle under fluctuating water supply conditions.

14. In a drinking fountain, the combination of a bowl having a drain opening and a supply passage, with a nozzle adapted to 65 deliver an arched drinking stream, a tubular nipple open to said supply passage provided with a vent opening, a gravity member mounted upon said nipple movably opposite said vent opening, said member being provided with a rounded bottom and an inclined skirt surrounding said rounded bottom against which the vented water is directed, said member being arranged and adapted to stabilize the drinking stream during fluctuation of the water supply. 75

In testimony whereof, I affix my signature to this specification.

HALSEY W. TAYLOR.
